UNITED STATES PATENT OFFICE.

WILLIAM P. ARMSTRONG, OF WASHINGTON, DISTRICT OF COLUMBIA, ASSIGNOR TO
THE STRONG ARM MANUFACTURING COMPANY, INCORPORATED, OF VIRGINIA.

EXERCISING DEVICE.

1,007,628.

Specification of Letters Patent. Patented Oct. 31, 1911.

Application filed January 27, 1911. Serial No. 604,941.

To all whom it may concern:

Be it known that I, WILLIAM P. ARMSTRONG, a citizen of the United States, and resident of Washington, District of Columbia, have invented certain new and useful Improvements in Exercising Devices; and I do hereby declare the following to be a full, clear, and exact description of the invention, such as will enable others skilled 10 in the art to which it appertains to make and use the same.

The invention relates to an improved exercising device particularly adapted for use as an aid to the acquirement of the art of boxing. It is intended as a substitute for punching bags and similar devices, to afford strenuous exercise of substantially the same kind, but combined with additional movements that develop strength, quickness and agility; and it is of such character that as a result of its close imitation of the form and re-action of a human opponent it serves not only as an exercising device, but also as a dummy figure upon which carefully planned and studied blows and counter-blows may be effectively practiced and developed.

In U. S. Letters Patent No. 952,862, granted me on March 22, 1910, there is disclosed an exercising device of the general character to which the present invention relates, which device is made up essentially of three elements, namely, a rocking base, a body portion stuffed or inflated and made in simulation of a human body, and legs fastened to the base and carrying at their upper ends a support for the body portion. The dummy figure so constructed is an effective exercising device for general use, and is suitable for employment in places of amusement and in the ordinary gymnasium.

The object of the present invention is primarily to give to a dummy figure of that general character a new kind and range of movements so as to more completely adapt it for use in training boxers, the reaction of the figure being such that the figure tends to maintain or regain a fixed upright position with such a degree of persistency as to command the skill of a trained boxer in punching and side-stepping, to avoid quick return movements of the figure, and to per-

mit him to practice effectively carefully worked out blows and counter-blows. 55

In the patent above mentioned the base was so constructed that the figure did not offer sufficient resistance to displacement from the upright position, nor did it regain such position so readily upon being struck 60 as to afford the advantages of the present invention in the respects above indicated.

Moreover, in accordance with the present invention, means are provided for limiting, and producing a quick return from, the extreme downward movement of the figure under a heavy blow, and the device is otherwise perfected in detail.

In the accompanying drawings forming a part of this specification Figure 1 is an 70 elevation of a dummy figure with the base partly broken away; Fig. 2 is a central sectional elevation of Fig. 1; Fig. 3 is an elevation partly in section on a larger scale, showing the construction below the waist-line more in detail; Fig. 4 is an elevation of the base partly in section, showing adjustable weights; Fig. 5 is a top plan view of the base of Fig. 1; Figs. 6 and 7 are respectively a central sectional elevation and a bottom 80 plan view of a base having certain modifications; and Fig. 8 is a vertical section of a base embodying further modifications.

The device consists of a base 1 and a dummy figure 2, which is preferably of the size 85 and proportions of a man, though smaller sizes may be made for the use of boys; and the improved base, and other details, of the present invention are adapted for use in connection with other forms. The figure as 90 shown stands on the base and is composed of a supporting part 4 comprising the legs, and a body portion 5 which is preferably inflated, though a stuffed body may be used, the body portion preferably being made in 95 simulation of the trunk and head of a man. The legs are preferably made of papier-mâché, leather or light material of sufficient stiffness to retain their shape, and are braced by the wooden disks 6, each leg being supported by an upright bar or rod 7, these bars in the construction shown, being made of pipe sections. For the reception of the ends of these pipe sections the base 100 contains two sockets 8, fastened to the base 105 at 9 and have centrally placed within them

conical pins or expansion wedges 10. With this combination the figure is fastened to the base by dropping the open ends of the pipe sections in the sockets over the conical pins, 5 on which they are firmly held by friction. The figure may, however, be removed from the base by lifting the ends of the pipe sections out of the sockets. The upper ends of the pipe sections screw into sockets 11 10 fastened at 12 to the disk 15 of wood or metal. The head and trunk of the figure, and the arms if desired are made of any suitable material, such as canvas or leather 14 in one or more pieces sewed together, 15 pulley around the plate 13 and drawn tightly at 15. The trunk and head may be stuffed with padding or the like, but preferably contains a closed air bag 16 of rubber or the like, inflated at the valve 17 so as to 20 extend the inclosing sack. The air bag is gotten in or out through a slit 18 in the sack, which may be laced as shown in Fig. 3. With this construction the entire trunk and head of the figure may be struck without 25 injury to the hands of the boxer.

The figure may be dressed to imitate the appearance of a man with shoes 19, stockings 20, and gymnasium trunks 21, while the exterior may be painted as desired to 30 represent characteristic features.

If desired, I may make the body portion of the figure of a solid construction, as, for example, a suitably molded or shaped block of papier-mâché or other appropriate 35 material in which event said body is covered with a soft outer covering such as would be afforded by layers of felt or similar material which would prevent injury to the hands of the boxer.

40 Although the above constructions may be considerably modified without departing from the essential features of the invention, it will be obvious that the construction shown herein lends itself well to a dummy 45 figure securely fastened to a base and presenting to the exerciser a proper proportion of head and trunk of sufficient resiliency and softness to maintain its form and receive the blows without injury to the exerciser.

50 The new range and character of movements above suggested are attained by means of the novel construction of the base 1, which consists of an outer shell 22 of suitable material such as iron, filled with heavy 55 substance such as iron, lead, stone or the like 23 to give the requisite weight, and closed on top by a plate of metal or wood 24. The top plate 24 is fastened to the shell 22 by means of bolts or screws 25. The base may 60 be provided with cups 26 of the desired number and distribution, into which weights 27 may be inserted at the will of the operator, in order to change the weight of the base and modify the movements of the figure. It is apparent that such adjustable

weights may be fastened to the base in any suitable manner, the essential thing being that they shall not become detached at any normal position of the figure and may be altered at the will of the user.

70 The rapidity of movement of the figure, the persistency with which it maintains or regains a fixed upright position, and the normal limit of extreme downward movement, are features of great importance, and it is by properly shaping and proportioning the base that the desirable character of these movements, as above suggested, is attained. For the intended purposes it is desirable

75 that under relatively light blows the figure should rapidly vibrate about the upright position, and should attain a rolling or oscillating movement only under a heavy blow, so that under a light leading blow the figure will not be greatly removed from the upright position, and will return very quickly thereto, whereas under a heavy blow the figure will be thrown far out of its upright position and will return more slowly, the reaction being thus brought to correspond

80 more closely to the conditions of an actual boxing match, and permitting the effective practicing of combinations of blows. To this end the base is provided with a flattened portion 30 of considerable extent, so that

90 any blow which is relatively light merely tips the base up on the edge of the flattened portion from which, by reason of the weight of the base it quickly returns; and this flattened portion merges into a curved rolling

95 surface as shown so that if a heavy blow is directed to the figure the base will be thrown beyond the flat onto the rolling surface and the return oscillation will have more nearly

100 the movement of a pendulum until the flattened portion is again reached, whereupon the figure vibrates rapidly about the upright position, thereby being brought to rest much more quickly than is the case when a base of the form shown in the patent above referred to is employed.

105 For the purpose of limiting the downward movement of the figure and causing a rebound or quick return under a knock-out blow, there is provided a projecting lip 31 around the periphery of the base. This lip may be fastened directly on the top piece 24, as shown, or the effect may be produced by attaching a suitable lip, such as a circular pipe section, to the rim of the base.

115 The rapidity of the movement of the figure depends upon the weight and its distribution and further upon the shape of the rounded surface 32 between the flat portion and the projecting lip 31. When the figure is struck with sufficient impact to move the base off its flat part 30, the base rolls on the rounded part 32, thereby continually shifting the point of contact, the weights acting downward on the two sides of that

point. The figure then continues to roll in its initial direction until the momentum existing in the mass, as a result of the blow imparted to it, just balances on the two sides of the point of contact. The figure then starts to return and continues its return movement until equilibrium is again produced at some point of contact on the other side of the vertical. If the radius of curvature of the surface 32 is increased, the time of a single vibration is normally increased and the movement becomes less rapid; whereas if the radius of curvature is reduced the time of vibration is reduced and the movement hastened. Hence it is obvious that the range of curvature at different parts of the surface may be so varied that substantially any desired character of reaction may be obtained.

Under the effect of a heavy blow the oscillating movement on the return, will be carried over the flat, and will be gradually reduced in its extent by friction until the momentum of the moving mass is insufficient to force the figure over the flat portion, when it quickly settles to rest in a fixed upright position. In the construction of the present invention this oscillating movement back and forth across the flat on to the rounded surface at opposite sides of the base, is much more quickly changed into the vibratory movement due to the flattened portion of the base, than is the case in the prior patent above referred to, and the liveliness and substantial similarity to the actual conditions of a boxing match is thereby greatly increased. The rounded surface 32 extends entirely around the base, so that the oscillating movement is not confined to any one plane but circular or twisting movements may occur simultaneously with the rolling movement.

If the figure be struck with sufficient force to roll it over until the projecting lip 31 comes into contact with the floor, the downward movement is suddenly arrested and the figure is caused to rebound to the upright position.

In Figs. 6 and 7 there is illustrated an arrangement in which the rolling surface of the base is provided with balls 28, in radiating channels 29, or according to any other arrangement, for the purpose of increasing the rapidity and range of movements by decreasing the friction at the rolling surface, if such increased rapidity and range is desired.

In the modification shown in Fig. 8, the base 35 is formed of a cast metal shell heavily loaded at the bottom and provided with thin side walls 36. The top plate of the previously described forms is omitted and the base is so shaped as to afford a solid portion 37 depressed below the top edge of the base, for the connection of the legs 7.

In other words, the bottom portion of the shell is made considerably thicker than the side portions and the top of said bottom portion serves to support the figure more or less directly. The base 36 is preferably cast in interlocked relation with a block 38 which is suitably formed to receive and position the legs of the figure, prior to the incorporation of said block in the main portion of the base by the aforesaid casting operation. In the embodiment shown, the block 38 is provided with spaced sockets in its upper surface in which coil springs 39 are secured at one end, the opposite ends of the springs being free. The tubular leg rods or bars 7 are secured to the base simply by fitting them over these springs, to which they closely conform, said rods or bars being maintained at the proper distance from each other by means of a plate 40 having openings through which said rods are passed and which lies on the top face of the block 38. The size of the recesses in block 38 are such that the bars 7 are capable of lateral movement in all directions, such movement being transmitted to the legs simultaneously by means of the connecting plate 40. By arranging the springs in the manner claimed, the figure can obviously be given a slight rocking or yielding movement with respect to the base, under the action of the blows given it, and the springs thereby have a cushioning effect which will be readily understood. In order to deaden the noise occasioned by the rocking of the base, and to obtain quick returns of the latter, I may associate a yielding or elastic cushioning member with the upper edge portion of the base.

In the drawing, I have shown a rubber cushioning member 41 of annular form held in a groove at the outer upper portion of the base in such a manner as to contact with the floor when the base is rocked to and fro to the extent permitted by the ordinary use of the contrivance.

In Fig. 2, I have shown diagrammatically a contrivance which may be used to advantage when the exerciser is exhibited at theatrical performances.

It will be readily understood from the foregoing description that the dummy figure is readily detachable from its base and that such detachment may be effected simply by lifting the figure out of the base sockets. In order to raise the figure quickly from the base and thereby bewilder the boxer who is occupying the attention of the spectators, I connect the upper portion of the figure by means of a suitably directed fine wire 45 to a suitably supported counterweight 46 located behind the scenes, which counterweight can be readily removed from its support in order to produce its downward movement and a corresponding and quick

rising movement of the dummy figure. The bewilderment or apparent bewilderment of the boxer, as the figure is caused to disappear quickly in a vertical direction as he is

5 prepared to strike it, will obviously create considerable amusement among the spectators.

What I claim is:—

1. In an exercising device of the character described, a dummy figure, and a base therefor having a rolling surface, a portion of said surface being flat so that the figure persistently tends to maintain or regain a fixed position; substantially as described.
- 10 2. In an exercising device of the character described, a base having a peripheral projecting lip which tends to limit the downward movement; substantially as described.
- 15 3. In an exercising device of the character described, a base having a flat portion on its under surface, a projecting lip near its outer periphery and a curved surface connecting the flat portion and the projecting lip; substantially as described.
- 20 4. In an exercising device of the character described, a base having a flat portion on its under surface, a projecting lip near its outer periphery, and curved surfaces of differing radii connecting the flat portion and the
- 25 30 projecting lip; substantially as described.
- 25 5. In an exercising device of the character described, a base, and a device on the base for attachment of weights, said device comprising a cup set in the top portion of the base; substantially as described.
- 30 6. In an exercising device, a rocking base and a dummy figure fastened thereto, the base having a flat portion on its under surface so that the figure persistently tends to maintain or regain a fixed position; substantially as described.
- 35 7. In an exercising device, a base and a dummy figure fastened thereto, the base having a peripheral projecting lip which tends to limit the downward movement of the figure; substantially as described.
- 40 8. In an exercising device, a base and a dummy figure fastened thereto, the base having a flat portion on its under surface, a projecting lip near its outer periphery and a curved surface connecting the flat portion and the projecting lip; substantially as described.
- 45 9. In an exercising device, a base and a dummy figure fastened thereto, the base having a flat portion on its under surface,

a projecting lip near its outer periphery and curved surfaces of differing radii connecting the flat portion and the projecting lip; substantially as described.

10. In an exercising device, a base, a dummy figure supported thereon, and means affording weight-holding cups or sockets at different points on the top portion of the base; substantially as described. 65

11. In an exercising device, a rocking base, and a dummy figure resiliently supported thereon; substantially as described.

12. In an exercising device, a rocking base movable freely over the floor, a dummy figure having depending leg rods, and springs connecting the lower ends of said rods with the base; substantially as described. 70

13. In an exercising device, a rocking bowl-like base having sockets at its upper 75 part, coiled springs rising in said sockets, and a dummy figure having tubular leg bars fitting at their lower ends over said springs and movable laterally in the sockets; substantially as described. 80

14. In an exercising device, a bowl-like rocking base having an annular cushioning member extending around the outer surface of the upper edge portion of said base; substantially as described. 85

15. In an exercising device, a rocking base comprising a bowl-like body having a thickened bottom portion, and a block having means for the attachment of a dummy figure and about which said body is cast in 90 interlocked relation; substantially as described.

16. In a device such as described, the combination of a base, a dummy figure supported thereon and freely removable therefrom in a vertical direction, and means for elevating the figure from the base; substantially as described. 95

17. In a device such as described, the combination of a base, a dummy figure supported thereon and freely removable therefrom in a vertical direction, and a counterweight having a connection with said figure by which the latter is raised away from the base; substantially as described. 100 105

In testimony whereof I affix my signature, in presence of two witnesses.

WILLIAM P. ARMSTRONG.
